UNITED STATES PATENT OFFICE

107,379

DESIGN FOR AN ELECTRICAL CONNECTING CAP

Raymond E. Patten and Gordon W. Florian,
Bridgeport, Conn., assignors to General Elec-
tric Company, a corporation of New York

Application August 27, 1937, Serial No. 71,352

Term of patent 14 years

To all whom it may concern:

Be it known that we, Raymond E. Patten and Gordon W. Florian, citizens of the United States, residing at Bridgeport, in the county of Fairfield, State of Connecticut, have invented a new, original, and ornamental Design for an Electrical Connecting Cap, of which the following is a specification, reference being had to the accompanying drawing, forming a part thereof.

In the drawing, Fig. 1 is a side view and Fig. 2 is an end view of an electrical connecting cap, showing our new design.

We claim:

The ornamental design for an electrical connecting cap, as shown.

RAYMOND E. PATTEN.
GORDON W. FLORIAN.
